UNITED STATES PATENT OFFICE.

ADAM NICKEL, OF NEW YORK, N. Y.

REPEATING ACTION FOR GRAND PIANOS.

SPECIFICATION forming part of Letters Patent No. 785,181, dated March 21, 1905.

Application filed December 20, 1904. Serial No. 237,850.

To all whom it may concern:

Be it known that I, ADAM NICKEL, a citizen of the United States, residing at New York city, Manhattan, county and State of New York, have invented new and useful Improvements in Repeating Action for Grand Pianos, of which the following is a specification.

This invention relates to a repeating action for grand pianos which is sensitively responsive to the touch and prevents lingering of the hammer at the string.

In the accompanying drawings, Figure 1 is a side elevation, partly in section, of my improved piano-action, showing the normal position of the parts; and Figs. 2 and 3 are similar views of part of the action, showing consecutive positions of the jack before and after the hammer has struck the string.

The letter *a* represents the key of a grand-piano action. *b* is the support, fulcrumed at *b'*, and *c* the lever, pivoted to the support at *c'*. The hammer *d*, resting with its shank upon the knuckle *c'* of the lever *c*, is pivoted at *d'* to the flange *e'* of the hammer-rail *e*. The jack *f* is made in the form of an elbow-lever and is pivoted at its lower bend or elbow to the forward end of the support *b*, as at *f'*. The lower or substantially horizontal arm of the jack projects forward from support *b* and has a beveled upper surface, which is adapted to be operatively engaged by an escapement-button *e*. The upright arm of the jack is slotted at its upper end for the reception of the lower end of a link *g*, which is pivoted thereto at *g'*. The upper end of link *g* is received by the slotted forward end of lever *c*, to which it is pivoted at *g''*. From the front of the jack projects upwardly a nose *h*, which is adapted to engage the forward end of lever *c* and the rear cushioned side *e* of rail *e*, such nose serving to limit the play of the jack. In order to adjust such play, a regulating-button *i*, projecting from the back of the jack, is adapted to contact with a shoulder *b* of support *b*. The jack *f* and link *g* are influenced by a spring *j*, depending from lever *c* and connected to link *g* by thread *j'*. If the key is in its normal position, the

jack *f* and link *g* form a reentrant obtuse angle, Fig. 1. Upon a depression of the key the support *b* is swung upward on pivot *b'*, so that the hammer is thrown against the string. Shortly before the string has been struck the lower arm of jack *f* will be engaged by the button *e*, Fig. 2, which will throw the upper end of the jack *f* and the lower end of the link *g* forward to form a salient obtuse angle, Fig. 3, which is smaller than the reentrant angle formerly formed. In this way the combined length of the parts *f g* is reduced, so that the lever *c* will descend at its forward end and the hammer will recede from the string. Upon the partial or full release of the key the spring *j* will return all the parts to their normal position, Fig. 1.

The nose *h* has the following function: Upon a powerful stroke of the key the felt of button *i*, being near the fulcrum *f'*, is compressed, and thus the center *g'* tends to move backward unduly. This is prevented by the nose *h* striking the front of lever *c*. After a powerful stroke of the key the contact of the nose *h* with the hammer-rail *e* prevents the upper end of the jack from flying forward to an excessive extent, so that the spring *j* can readily draw the jack back into its normal position.

It will be observed that the construction of the escapement is such that the button *e* will first engage the lower arm of the jack near its free end, Fig. 2, to start the jack and will then engage such arm nearer to its fulcrum, Fig. 3, to throw the jack forward with increased rapidity. The result is that a very sensitive escapement is obtained and lingering of the hammer at the string is prevented.

What I claim is—

1. A repeating action for grand pianos, provided with a support, an elbow-shaped jack pivoted thereto at its bend, and having a beveled lower arm, an escapement-button adapted to operatively engage said arm, a hammer-supporting lever, and a pivoted link which connects the jack to the lever, substantially as specified.

2. A repeating action for grand pianos, provided with a support, an elbow-shaped jack pivoted thereto at its bend, an escapement-button adapted to operatively engage

the lower jack-arm, a hammer-rail, a hammer-supporting lever, a pivoted link which connects the jack to the lever, and a nose projecting upwardly from the jack and adapted to engage the hammer-rail and the lever, substantially as specified.

5 Signed by me, at New York city, (Manhat-

tan,) New York, this 17th day of December
1904.
